(Vedder & Anderson)
Design for Stove.

Maren, Swettland & Little of Half Moon Village N.Y.

Assignees of
Bedder and Sanderson of Troy N.Y.
Letters Patent No 449 Dated Feb 24th 1852

The schedule referred to in these Letters Patent and making part of the same.

To all to whom these presents shall come,

Be it known that we
N. S. Bedder and William L. Sanderson of Troy in the County of
Rensselaer and State of New York, have invented or produced a new
design of Parlor or Office stove which we call the "Saratoga Coal
burner" and we do hereby declare that the following is a full
and exact description of the same, reference being had to the
annexed drawings making a part of this specification in which
fig A is a view of the top plate, fig B is a view of the bottom
plate, fig C is a view of front plate, fig D is a view of the hearth
fig E is a view of the register plate fitting on the hearth fig F
is a view of the urn, fig G is a view of the cover and fig H
is a view of the leg.

Our design consists of Gothic Window-arch
door, arches a & b and niches c & c and arabesque ornaments
mouldings &c disposed on the various parts of the stove as
represented.

Having thus described our design of stove
what we claim, and desire to secure by Letters Patent is the
design and configuration of stove substantially the same
as described and represented on the annexed drawings
